UNITED STATES PATENT OFFICE.

RICHARD SCHOCH, OF NEWARK, NEW JERSEY.

METAL CLOTH FOR PURSES, CHATELAINE-BAGS, &c.

SPECIFICATION forming part of Letters Patent No. 689,232, dated December 17, 1901.

Application filed May 15, 1901. Serial No. 60,282. (No model.)

To all whom it may concern:

Be it known that I, RICHARD SCHOCH, a citizen of the United States, residing at Newark, in the county of Essex and State of New Jersey, have invented certain new and useful Improvements in Metal Cloth for Purses, Chatelaine-Bags, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to secure a metal cloth adapted for chatelaine-bags or other purses which will be of unique appearance, strong, and durable, to avoid the use of solder in the production of such metal cloth, to reduce the cost of construction, and to secure other advantages and results, some of which may be referred to hereinafter in connection with the description of the working parts.

The invention consists in the improved metal cloth for purses, chatelaine-bags, &c., and in the arrangements and combinations of parts of the same, all substantially as will be hereinafter set forth, and finally embraced in the clauses of the claim.

Referring to the accompanying drawings, in which like letters of reference indicate corresponding parts in each of the several views, Figure 1 is a side elevation of a chatelaine-bag employing the cloth of my improved construction. Fig. 2 is a detail view of a collection of links, on a greatly-enlarged scale, to show the construction of the cloth more clearly. Fig. 3 is a side view of the same. Fig. 4 is a plan of what I call the "pearl link" in blank. Fig. 5 is a view of the said pearl link in rear elevation struck up to receive the connecting-link. Fig. 6 is a side elevation of the same. Fig. 7 is a plan of one of the links for connecting the pearls to the frame of the bag. Fig. 8 is a detail of a link for connecting two pearls. Fig. 9 is a view of a connecting-link adapted to be employed as a stone-setting; and Fig. 10 is a rear view showing the connection of the stone-

setting link and other parts, all as will be hereinafter more fully described.

In said drawings, *a* indicates a bag or purse of any suitable design or construction. *b* indicates the metal cloth from which the body 55 of the said bag is constructed.

c indicates the pearl links, and *d* the connecting-links. Said pearl links comprise plates of metal (shown in detail in blank in Fig. 4) having a series of arms *c'* *c'*, which are first bent up, as indicated in Fig. 6, so that the plate is cupped or made concavo-convex, and at the periphery of the pearl are provided with a series of sockets *c*², into which the shank *d'* of the connecting-link *d* 65 may pass. The said arms *c'* after the said connecting-links are in place in the sockets of the pearl link are bent inward, as indicated in Figs. 2, 3, and 10, closing the sockets for the connecting-links, so that the latter are held securely in place within the pearl link. The connecting-links *d* are formed as shown in Fig. 8, in which at the opposite ends of the shank are shown cross-heads *d*², 70 adapted to lie inside of the closed pearl, the 75 said cross-heads being at their edges curved or inclined, as at *d*³, to more or less closely conform to the concave curvatures of the inside walls of the pearl.

When I desire to employ jewels in connection with the links *d*, I form a stone-setting *d*⁴ in connection with shanks *d'*, four of the said shanks being integrally united with a plate of metal recessed to receive the stone and provided with stone-holding fingers *d*⁵, 85 adapted to be bent around the edges of the stone after the fashion of an ordinary stone-setting. In the formation of the cloth the stones may take the place of certain of the pearls first described, as indicated in the 90 drawings, and thus give ornamental character to the bag, and the arrangement of the stone-settings may be varied at will, so as to make a greater variety in the ornamentation of the bag.

It is evident that the shape of the pearl may be varied at will and be given a diamond or other shape in face ornamentation.

Having thus described the invention, what I claim as new is—

1. The combination, in a metal cloth, of concavo-convex plates each having at its periphery a series of arms bent backwardly and inwardly, and connecting-links with cross-heads at opposite ends joining one plate with another, substantially as set forth.

2. The improved metal cloth comprising links having a series of arms with sockets or recesses between and connecting-links having cross-heads at opposite ends, the shanks between said opposite cross-heads lying in

said sockets and the cross-heads in the concave interior of said links with arms, substantially as set forth.

In testimony that I claim the foregoing I 15 have hereunto set my hand this 18th day of April, 1901.

RICHARD SCHOCH.
